UNITED STATES PATENT OFFICE.

FREDERICK GRETER, OF AKRON, OHIO.

PAD FOR CLEANSING GLASS SURFACES.

SPECIFICATION forming part of Letters Patent No. 789,421, dated May 9, 1905.

Application filed August 1, 1903. Serial No. 167,856.

To all whom it may concern:

Be it known that I, FREDERICK GRETER, a citizen of the United States, residing at Akron, in the county of Summit and State of Ohio, 5 have invented certain new and useful Improvements in Pads for Cleansing Glass Surfaces; and I do declare that the following is a full, clear, and exact description of the invention, which will enable others skilled in the art 10 to which it appertains to make and use the same.

My invention relates to pads for cleaning glass surfaces such as mirrors, show-cases, windows, and the like where thorough cleansing 15 is desired.

In the accompanying drawings, Figure 1 is a perspective elevation of my new and improved pad. Fig. 2 is an edge elevation thereof, showing one end bent forward and 20 down to reverse the keeper to the other side.

The pad thus shown is essentially a hand-pad and is designed to be gripped and used by hand alone and not by a mechanical gripping or holding device of any kind. My invention is therefore to be understood as different in this particular from what are known as "window-washers" with special holders and handles, as well as different from any and all devices in this art which call for mechanical 25 appliances of some kind to enable them to be used.

In the construction of a pad A adapted to be used as in this invention several things are of importance. Thus, for example, the 30 pad should have size and shape which are convenient to be held by the hand, and for this reason I have adopted, preferably, a substantially rectangular shape, with a length, say, of about four inches and a width of about 35

three inches and a thickness of about one inch. These are approximate figures and may be departed from more or less either way. Then, again, the quality of the bag or cover is important, because it must be such as will not 40 scratch or mar the glass over which it is rubbed and at the same time flexible and fairly porous. I have found that what is known as "canton-flannel" with its woolly side outside, is admirably adapted to this use. It has the 45 requisite softness so as not to injure the glass, and while it is porous it is woven closely enough to retain the body of the material within the

pad, which does not dissolve in use. The compound or filling of the pad is of a character which serves first of all the purposes of cleansing, so that when the pad has been moistened by dipping it in water there will be at least measurable dissolving of the cleansing ingredients and a corresponding working out or exuding thereof through the cover, so as to serve its purpose. However, it should be understood that this pad is designed to be used over and over again during different days before becoming exhausted, and hence in the selection or preparation of a compound 55 its continued or repeated use should be taken into account. As a suitable filter or body for the pad I mention sawdust, and especially cedar sawdust, and a mixture of substantially equal parts of bicarbonate of soda and whiting. Finally, the pad thus constructed and filled is preferably provided with a hand loop 60 or keeper B. This enables the four fingers of the hand to be slipped through the keeper and to rest the hand flat thereon, and thus most 65 conveniently and effectively handle the pad; but it is desirable to not only have a keeper which will engage quite snugly over the fingers, but which will allow the pad to be reversed and used on either side. To this end 70 the keeper is made just large enough to bend one end of the pad through it, as seen in Fig. 2. By reason of the pad being flexible I can 75 use a comparatively small loop or keeper B and which will rest well down upon the fingers and help hold the pad when the fingers 80 are spread out thereon.

Any one skilled in the use of a pad of this kind will soon detect when it is "exhausted"—that is, when the cleansing ingredients 85 are all washed out.

What I claim is—

As a new article of manufacture, a hand-pad for cleansing mirrors and other glass surfaces having a porous fabric cover and a filler consisting of sawdust and a cleansing mixture of bicarbonate of soda and whiting intermixed with the sawdust, substantially as described. 95

Witness my hand to the foregoing specification this 11th day of July, 1903.

FRED. GRETER.

Witnesses:

JOHN GRETER,
BLANCHE ALLYN.
